CLAIM

The ornamental design for a display screen or portion thereof with an animated graphical user interface, as shown and described.

DESCRIPTION

FIG. 1 is a front view of a first image in a sequence for a display screen or portion thereof with an animated graphical user interface, showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof; and,

FIG. 7 is a front view of a seventh image thereof.

The broken lines shown in the drawing illustrate a device and/or portions of the display screen or portion thereof with an animated graphical user interface that form no part of the claimed design.

The appearance of the animated image sequentially transitions between images shown in FIGS. 1 through 7. The (Continued)

process or period in which one image transitions to another image forms no part of the claimed design.
